UNITED STATES PATENT OFFICE.

CHARLES DE QUILLFELDT, OF NEW YORK, N. Y., ASSIGNOR TO DONALDSON BROTHERS, OF SAME PLACE.

PAPER POCKET-BOOK.

SPECIFICATION forming part of Letters Patent No. 276,961, dated May 1, 1883.

Application filed March 3, 1883. (Model.)

To all whom it may concern:

Be it known that I, CHARLES DE QUILLFELDT, of the city, county, and State of New York, have invented certain new and useful 5 Improvements in Paper Pocket-Books, of which the following is a specification.

This invention has reference to an improved pocket-book made of two pieces of paper that are connected without pasting or stitching, 10 such a manner that two pockets are formed; and the invention consists of a pocket-book made of a main piece and an auxiliary piece, which latter forms, with side gussets and extension-flaps of the main piece, one of the 15 pockets of the book. The main piece is made of a continuous blank, the oblong rear and front parts of which are connected by a bottom part, both the rear and front parts being provided with side gussets having lateral ex- 20 tension-flaps. The front part and its side gussets and extension-flaps form, with an extension-piece having a binding-flap, the second pocket of the book. The rear wall is provided with a closing top flap having locking-tongues 25 that enter slots of the front wall.

In the accompanying drawings, Figures 1, 2, 3, 4, and 5 represent, respectively, a front view, a vertical transverse section in closed position, a vertical transverse section in open position, 30 an end view, and horizontal section of my improved paper pocket-book; and Figs. 6 and 7 are the blanks, respectively, of the auxiliary and main pieces of which the pocket-book is formed.

Similar letters of reference indicate corresponding parts.

A in the drawings represents the main piece, and B the auxiliary piece, of my improved paper pocket-book.

The main piece A (shown in Fig. 7) is composed of a rear part, a , and a front wall, a' , both connected by a bottom portion, a^2 . The rear and front walls, a and a' , are made of oblong shape, and provided with side gussets, b and b' , and lateral extension-flaps d and d' . A locking-flap, e , extends from the front wall, a' , and is provided with a binding-flap, e' , which latter is folded down over the edge of the inwardly-bent extension-flaps d and d' of the side gussets.

b and b' , so as to lock them together and form a 50 pocket with folding side gussets. At the upper end of the rear wall, a , is arranged a closing-flap, f , that is provided with locking-tongues f' , that enter into slots f^2 of the front wall, a' , so as to close the book. The tongues f' and f^2 are made integral with the blank A, and may be made of any other suitable shape or construction, as I do not confine myself to the special locking device shown.

The auxiliary piece B is made of an oblong 60 middle portion, g , of the same size as the front and rear walls, a and a' , an upward extension, g' , of the same size, and a narrow retaining-flap, g^2 , at the lower edge. This auxiliary piece B is applied to the extension-flaps d and d' of the 65 rear part, a , by first inserting the part g' along the rear wall, a , back of the side gussets b and b' , then bringing the middle portion, g , over the outside of the inwardly-folded extension-flaps d and d' , and finally folding the retaining-flap g^2 70 down over the edge of the flaps d and d' , so as to form therewith a second pocket with folding side gussets, as shown in Figs. 3 and 4. When closed by the top flaps, the pockets fold partly together and meet on a diagonal line, 75 as shown in Fig. 2. In this manner a pocket-book is obtained that is made of two pieces, so as to form two pockets, the parts of which are connected without pasting or stitching, and forms a neat device for advertising and 80 other purposes.

Having thus described my invention, I claim as new and desire to secure by Letters Patent—

1. A paper pocket-book having two pockets, made of a main piece, A, composed of a rear 85 wall, a , connecting-bottom a^2 , front wall, a' , the rear and front walls having folding side gussets, b and b' , and lateral extension-flaps d and d' , respectively, retaining-flaps e and e' , and closing top f , and an auxiliary piece, B, formed 90 of sections g and g^2 , the auxiliary piece being applied to the extension-flaps d and d' of the rear wall, so as to form a pocket therewith, while the retaining-flap e forms a pocket with the extension-flaps d and d' of the front wall, a' , and a locking device, f and f^2 , made integral with the main piece A, substantially as set forth.
2. A blank for a paper pocket-book formed of

a rear wall, a , bottom a^2 , front wall, a' , the rear and front parts having folding side gussets, b b and $b' b'$, and lateral extension-flaps d d and $d' d'$, respectively, a retaining-flap, e e' , and a closing top flap, f , having locking-tongues f' , integral therewith, fitting into slots f^2 f^2 of the front part, substantially as set forth.

In testimony that I claim the foregoing as my invention I have signed my name in presence of two subscribing witnesses.

CHAS. DE QUILLFELDT.
